D 2-20. OR D 13,410 EX

No. 13,410

Nov 14, 1882

UNITED STATES PATENT OFFICE.

JOHN L. POPE, OF CLEVELAND, OHIO.

DESIGN FOR A WEAR-IRON.

SPECIFICATION forming part of Design No. 13,410, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and 5 original Design for Wear-Irons, of which the following is a specification, reference being had to the accompanying engraving, forming part thereof.

My invention relates to a design for the wear- 10 irons of carriages and other vehicles; and it consists in the general shape of the article, as well as in certain features of ornamentation thereof.

In the engraving which accompanies this 15 specification, A A will be found to designate two elongated lug-like portions through which are made two holes, as at b b, for attachment of the contrivance by screws to the body or other portion of the vehicle, as usual. The 20 ends of the iron are formed into horn-like portions B B', with knob-like or swelled points c c', the former inclined upwardly and the latter inclined downwardly. Along the upper edge of the iron, and extending around the 25 horns B B', is a rib, a, as shown. The arch-like portion between the two lugs A A is similarly ribbed. On either side of this arch-like part I have shown the body of the iron embellished with a foliated ornament, e, in open-work.

Having so fully described my new design, what I claim as of my invention, and desire to secure by Letters Patent, is—

1. A wear-iron comprising the lugs A A and horns B B'.

2. A wear-iron composed of lugs A A, connected by a ribbed arch.

3. A wear-iron with a rib or flange along its top edge and along the borders of the horns B B', forming parts of said wear-iron.

4. A wear-iron having the body thereof ornamented with foliated open-work, substantially as shown and described.

In witness whereof I have hereunto set my hand this 22d day of June, 1882.

JOHN L. POPE.
